UNITED STATES PATENT OFFICE.

GEORGE W. BROWNE, OF BROOKLYN, NEW YORK.

PORTABLE BLACKING-STAND.

SPECIFICATION forming part of Letters Patent No. 426,234, dated April 22, 1890.

Application filed June 22, 1889. Serial No. 315,196. (No model.)

To all whom it may concern:

Be it known that I, GEORGE W. BROWNE, of Brooklyn, in the county of Kings and State of New York, have invented a new and Improved Portable Blacking-Stand, of which the following is a full, clear, and exact description.

The object of the invention is to provide a new and improved blacking-stand which is simple and portable in construction, and can be conveniently folded up when not in use and readily transported from one place to another.

The invention consists of a foot-rest and a chair adapted to be folded on the said foot-rest.

The invention also consists of certain parts and details and combinations of the same, as will be hereinafter fully described, and then pointed out in the claims.

Reference is to be had to the accompanying drawings, forming a part of this specification, in which similar letters of reference indicate corresponding parts in all the figures.

Figure 1 is a perspective view of the improvement ready for use. Fig. 2 is a sectional side elevation of the same. Fig. 3 is a perspective view of the improvement as folded up, and Fig. 4 is a sectional side elevation of the same.

The improved blacking-stand A is provided with a back B, erected on the rear end of a base C, supporting the sides D and D', connected with each other at the top by a transverse plate E, carrying on its top the box F, having a front lid F', and serving to store blacking utensils. On the top of the box F are secured the shoe forms G, on which the party desiring to have his boots blacked can rest his feet.

In the space formed between the sides D and D', part of the back B, and the base C is fitted a drawer H, also serving to store the blacking utensils and other articles. Between the box F and the back B, on top of the bottom plate E, is held another box I, located between the shoe forms G and provided on top with a lid I'. This box I serves a similar purpose to the box F.

On the back B are arranged and hinged thereto the side plates J and J', extending rearward in line with the sides D and D'. On

top of the back B and the sides J and J' is adapted to rest a chair K, provided with a seat L, hinged at its front end to the top edge of the back B. The chair K is also provided with a back N and the side rails O and O', as plainly shown in the drawings. In order to fasten the chair K to the side plates J and J', each of the latter is provided with a hook J², engaging an eye L' at the rear edge of the seat L, as is plainly shown in Fig. 2. To the upper end of the back N of the chair K is hinged a transversely-extending board P, adapted to lock the drawer H in place when the stand is folded up, as shown in Figs. 3 and 4.

On the under side of the seat L is secured a handle Q, serving for conveniently pushing the blacking-stand when folded up. To the rear of the back B are secured suitable brackets R, in which is mounted to turn a transversely-extending shaft S, carrying the wheels T. On the rear of the back B, at U', is pivoted an L-shaped bracket U, carrying on its outer end a small wheel V. A short arm U² extends from the bracket U and is adapted to pass onto the base C when the stand is folded up, as shown in Figs. 3 and 4. A fastening device W, of any desired construction, is held on the base C, and serves to lock said extension-arm U² to the base, as is plainly shown in Figs. 3 and 4.

On the under side of the base C are arranged a number of projections C², and similar projections J⁴ are formed on the lower edges of the sides of the plates J and J', as shown in the drawings. The projections C² and J⁴ serve to conveniently hold the stand in place by embedding themselves in the ground.

When the stand is folded up, the side plates J and J' are fastened in place on the back N of the chair K by hooks N', secured on the back N of the chair K, and adapted to engage eyes J³, formed on one edge of the respective plate J or J', as is plainly shown in Figs. 3 and 4. The back N of the chair K is preferably surrounded on three sides by a low railing N², serving to hold papers and other articles when the stand is folded up, as shown in Figs. 3 and 4. When the stand is set up, as illustrated in Figs. 1 and 2, the side plates J and J' support the seat L of the chair K,

the latter being locked in place by the hooks J². The stand can now be used in the same manner as the ordinary fixed stands.

When the owner of the stand desires to move from one place to another, he first un-hooks the hooks J², then swings the chair K forward, so that the ends of the railing N² rest on the tops of the sides D and D'. The board P is swung in line with the back N of the chair K, and fastened by its hook P' on an eye C' held in the base C. (See Fig. 4.) The operator then swings the side plates J and J' to the front against the outsides of the sides D and D' and the sides of the chair K. The operator now fastens the side plates J and J' in place by moving the hooks N' on the back N into the eyes J³ on the said sides. The several parts are now locked in place and the operator tips the device over so that it rests on the wheels T T. The operator also swings the bracket U forward, so that the extension-arm U² fits against the base C, and the said extension-arm is locked in place by the catch W, so that the entire device now rests on the three wheels V and T T. The operator now takes hold of the handle Q, and by pushing the same can conveniently transport the blacking-stand to any desired place.

The lids F' and I' are preferably provided with suitable locks or bolts for locking them in place.

Having thus fully described my invention, I claim as new and desire to secure by Letters Patent—

35 1. A blacking-stand comprising a base having a vertical back and provided with a foot-rest, sides hinged to the side edges of the back, and a top hinged to the upper edge of the said back, substantially as described.

40 2. In a blacking-stand, the combination, with a base having a back and provided with a foot-rest, of a chair hinged at its front edge to the upper end of the back, whereby the chair is adapted to be folded down over the 45 foot-rest, with its back against the base, substantially as described.

3. In a portable blacking-stand, the combination, with a base having a back and provided with a foot-rest, of wheels journaled in 50 brackets projecting from the rear face of the back, substantially as and for the purpose set forth.

4. In a portable blacking-stand, the combination, with a folding casing consisting of 55 a base having a back and hinged top and sides, of wheels secured to the rear face of the back, substantially as and for the purpose set forth.

5. A portable blacking-stand comprising a

folding casing consisting of hinged sections, 60 one of the sections forming a seat which when not in use is inclosed in the casing, and wheels secured to the back section of the casing and adapted to be inclosed in the casing when the seat is in use, substantially 65 as described.

6. In a portable blacking-stand, the combination, with a back and sides hinged thereto, of a seat hinged at its front edge to the upper end of the back, substantially as described. 70

7. In a portable blacking-stand, the combination, with a back and sides hinged thereto, of a seat hinged at its front edge to the upper end of the back, and wheels secured 75 to the rear of the back, substantially as and for the purpose specified.

8. In a portable blacking-stand, the combination, with a base and a back secured to the rear edge thereof, of sides hinged to the 80 sides of the back, a seat hinged at its front edge to the upper end of the back, and means 85 for locking the seat to the sides when in use and to the base when not in use, substantially as described.

9. In a portable blacking-stand, the combination, with a base and a back projecting upward from its rear edge, of sides hinged 90 to the sides of the back, a seat hinged at the upper end of the back, wheels on the rear face of the back, and means for locking the seat to the sides when in use and to the base when not in use, substantially as described.

10. In a portable blacking-stand, the combination, with a base having a back projecting upward from its rear edge, side plates 95 hinged to the sides of the back, and a chair having its seat hinged to the upper end of the back, of hangers projecting from the rear face of the back, wheels journaled in said 100 hangers, a bracket pivoted to the rear face of the back, a wheel in the lower end of the bracket, and means for locking the bracket in position, substantially as herein shown and described.

11. In a portable blacking-stand, the combination, with a base and a back projecting from the same, of side plates hinged to the sides of the back, a seat hinged to the upper end of the back and provided with a sectional and hinged back, and means for locking the upper section of the seat to the base, substantially as herein shown and described. 115
